UNITED STATES PATENT OFFICE.

DAVID HUNTER, OF TROON, COUNTY OF AYR, ASSIGNOR OF EIGHTEEN-TWENTIETHS TO ALEXANDER DONALDSON SPIER AND ARCHIBALD SCOTT BROWN, BOTH OF GLASGOW, SCOTLAND.

APPARATUS FOR CLEANING THE SIDES AND BOTTOMS OF SHIPS.

SPECIFICATION forming part of Letters Patent No. 318,904, dated May 26, 1885.

Application filed July 1, 1884. (No model.) Patented in England September 11, 1883, No. 4,340, extended to the Island of St. Helena.

To all whom it may concern:

Be it known that I, DAVID HUNTER, a citizen of the United Kingdom of Great Britain and Ireland, residing at Troon, in the county 5 of Ayr, Scotland, have invented new and useful Improvements in Apparatus for Cleaning or Scrubbing the Sides and Bottoms of Ships Afloat, (for which I have obtained Letters Patent of Great Britain dated September 11, 10 1883, and numbered 4,340, which Letters Patent were extended to the Island of St. Helena on the 8th day of May, 1884, in accordance with the provisions of Ordinance No. 3 of 1872;) and I do hereby declare that the following is 15 a full, clear, and exact description of the invention, which will enable others skilled in the manufacture or art to which it relates to make and use the same.

This invention has for its object improvements in apparatus for cleaning, scrubbing, or removing from the sides and bottoms of ships or vessels while afloat, and either in motion or at anchor, incrustations or objectionable marine, animal, or vegetable matters.

25 The said invention relates to that class of such apparatus which is moved over the skin of the ship or vessel in an approximately vertical direction or through an arc from the keel toward the deck, and vice versa; and the apparatus as constructed under this invention 30 consists of a jointed or articulated frame carrying a brush, scrubber, or scraper, which is provided with means for holding or forcing it when in operation against the surface to be 35 cleaned or scraped, and for enabling it to override bilge-pieces or other projections on the hull.

In the accompanying drawings, Figure 1 is 40 a front elevation of the apparatus constituting the invention. Fig. 2 is an elevation of the end thereof marked A, Fig. 1. Fig. 3 is an elevation of the end marked B, Fig. 1. Fig. 4 is a plan of the cleaning or scrubbing brush as drawn on Figs. 1, 2, and 3. Figs. 45 5 and 6 illustrate alternative modes of constructing the brush. Fig. 7 shows the mode of operating the apparatus.

As seen at Figs. 1, 2, and 3, the apparatus 50 constituting the invention consists of an open frame composed of top and bottom members,

a, connected together at or near their ends by vertical tie-rods b, which pass through slots made in the parts a, and have holes or eyes made at their upper projecting ends to which lines c c' are secured. The parts a are made 55 flat on their upper and under sides to afford a surface on which the water-currents act, as hereinafter set forth, and they are attached to the ties b by pins d, on which they are capable of moving through a vertical arc on 60 the system of parallel rulers.

Between the two ties b, and preferably midway from the ends of the members a, the said members are further tied together by a bar or bars, e, the ends of the said bar or bars 65 passing into or through slots in the parts a, and the connecting-pins f thereof act as centers for the movement of the top and bottom members of the frame. A brush, g, flat, curved, or of any other suitable shape, is rigidly secured to the mid bar or bars, e; but, as seen on the drawings, it has no connection with the end ties, b. On the back of the said brush an inclined plane, h, is made or connected, the narrow end of the angle being at the forward 70 end of the brush. The inclined plane may be rigidly secured to the back of the brush by a stay or stays, i, as seen more particularly at Fig. 4, in which case its angle of inclination is permanent; or the said angle of inclination, in 75 order to adapt itself to the speed of the ship or vessel or to the speed or strength of varying currents, may be adjusted automatically, such adjustment being effected by placing a coil-spring between the back of the brush and 80 the inclined plane, as seen at j, Fig. 5. A plate or other equivalent spring may be substituted for the said coil-spring, suitable stops being in any case provided to prevent the angle of inclination from becoming either too 85 great or too little, the proper inclination being such as will at all times be sufficient to hold the brush in such frictional contact with the hull of the ship as to cause it in operation to remove the incrustations therefrom, while at 90 the same time it should not be so great as to render the vertical working of the brush difficult or impossible.

Between the narrow or forward end of the inclined plane h and the stay i, spring j, or 95

screw *k*, leather, canvas, or equivalent strips may be nailed or otherwise fastened, after the manner of the sides of a bellows, along the sides both of the brush *g* and the inclined plane 5 *h*, as indicated by the dotted lines, Figs. 4, 5, and 6, and so as to inclose the space between them, and tend to increase the efficiency of the apparatus by preventing the water-current from exerting a pressure on the stay, spring, 10 or screw.

Under another mode, illustrated at Fig. 6, the adjustment of the plane *h*, in lieu of being automatic, is effected by a screw, *k*, and nut *l*, a key being applied to the screw when it is 15 desired to alter the angle; or the said adjustment may be effected in any other convenient manner, it being understood that I do not confine myself to the modes hereinbefore set forth. At its forward end the brush *g* has a 20 line, *m*, attached to it, which line is passed through a block on the martingale, as seen at *n*, Fig. 7, or on other part of the ship in front of the apparatus, and thence to the deck, and the lines *c c'*, from the end ties, *b*, also pass to 25 the deck.

The operation of cleaning the hull of the ship or vessel is as follows: After the apparatus has been passed into the water, it is caused to sink by pulling the line *c* attached to the 30 rear end tie, *b*, of the frame and slackening the line *c'*, attached to the front end tie, which causes the frame to incline upward from its forward toward its rearward end. The forward movement of the ship causes the water 35 to act on the said inclined plane constituted by the members *a*, and carry the frame, and with it the brush, downward, the rear line, *c*, which is meantime kept only sufficiently taut to hold the frame in proper position, being 40 paid out as the apparatus sinks. While so descending, the brush is made to press against the ship's side, also by the forward motion of the ship, causing the water to act on the inclined plane *h*, by which means a scrubbing 45 effect is produced over an arc on the hull, the radius of which arc is greater or less, according to the distance of the brush from the block through which the head-line *m* passes. When the brush has been carried down to the keel, 50 the inclination of the frame is reversed by slackening the line *c* and pulling the line *c'*, whereby the apparatus is caused to ascend, and the water still acting on the inclined plane *h* and pressing the brush against the ship's 55 side an upward cleaning action is produced either on the same or on a new surface of the hull, the head-line *m* being from time to time paid out or drawn in, accordingly as the work is being effected from the bow toward the stern, 60 or vice versa. When one side of the ship has been cleaned, the lines *c c'* are connected to the other end of the ties *b*—that is to say, the apparatus is turned upside down and then passed over the other side of the ship and similarly 65 operated.

To enable the brush to override bilge-pieces or other projections on the ship's hull, it is

provided with rollers *o*, whose axes are supported in bearings on and are parallel to the length of the body of the brush, and the said 70 rollers also act to crush, loosen, and remove barnacles or other matters during the action of the apparatus.

The apparatus, besides being used in cleaning or scrubbing the hulls of ships or vessels 75 when in motion, may also be employed to remove incrustations when the ship or vessel is at anchor in tidal or other water-ways, where there is enough current to cause the brush to press against the hull with sufficient force by 80 acting on the inclined plane *h*.

The apparatus may also be usefully employed in clearing or brushing away obstructions from the mouths or outlets of water-closet, bilge, and other pipes, which frequently 85 become choked, and being under water are otherwise difficult to free without docking the ship.

Although I have shown a brush as used in the improved apparatus, it is to be understood 90 that a scrubber or scrubbers, or a scraper or scrapers, may be substituted therefor when desired.

I am aware that devices similar to the one herein described for cleaning the sides and 95 bottoms of vessels afloat have been provided with a number of small anti-friction wheels for enabling them to move easily over the surface to be cleansed, and also that in lieu of such small wheels convexed rollers have 100 been employed; but such are not the equivalents of my invention.

I am further aware that in similar devices, where it was thought desirable to employ a rotary brush, a drum has been employed for 105 imparting such rotation to the brushes, said drum deriving its rotation from contact with the ship's side. In this device, however, the drum is provided at close intervals with rubber rings, which are placed parallel to each 110 other and to the ends of the drum, whereby the friction is said to be increased and the rotation rendered more positive. None of these devices are capable of producing the result 115 produced by the continuous parallel-faced rollers employed in my device, nor were they ever intended to be by their respective inventors.

Having fully described my invention, what I desire to claim and secure by Letters Patent is—

1. In a device, substantially as herein described, for cleaning the sides and bottoms of vessels afloat, the combination, with a frame, of one or more rollers having solid continuous 125 parallel surfaces, which are adapted to bear from end to end flush against the surface to be cleansed for breaking the barnacles, as set forth.

2. In an apparatus for cleaning the sides and bottoms of vessels afloat, the combination, 130 with a suitable frame and a brush, of one or more rollers having continuous parallel surfaces adapted to bear from end to end flush against the surface to be cleansed, for break-

ing the barnacles so that they may be easily removed by the brush, as described.

3. In a device for cleansing the sides and bottoms of ships afloat, the combination, with
5 a frame, a brush, and means for moving it over the surface to be cleansed, of a roller having continuous parallel surfaces journaled in said frame, and carried thereby in advance of the brush, as and for the purpose set forth.
- 10 4. In apparatus for cleaning the sides and bottoms of ships afloat, a brush or cleaner having a fixed inclined plane on the back of it, and strips of leather, canvas, or equivalent material extending from it to the body of the
15 cleaner, substantially as described.

5. In apparatus for cleaning the sides and bottoms of ships afloat, a brush or cleaner having an adjustable inclined plane on the back of it, and strips of leather, canvas, or equivalent material extending from it to the 20 body of the cleaner, substantially as described.

In witness whereof I have hereunto set my hand and seal this 9th day of June, 1884.

DAVID HUNTER. [L. S.]
